UNITED STATES PATENT OFFICE

153,409

DESIGN FOR A COMBINED NECKLACE AND CLIP

Sol E. Weinreich, New York, N. Y.

Application January 8, 1949, Serial No. 133

Term of patent 7 years

(Cl. D45—16)

To all whom it may concern:

Be it known that I, Sol E. Weinreich, a citizen of the United States of America, residing in New York, county of New York, and State of New York, have invented a new, original, and ornamental Design for a Combined Necklace and Clip, of which the following is a specification, reference being had to the accompanying drawing, forming part thereof.

Fig. 1 is a plan view of a combined necklace and clip, showing my new design.

Fig. 2 is an edge view thereof.

Fig. 3 is a fragmentary view of Fig. 1, illustrating the necklace removed from the clip.

Fig. 4 is a rear view of Fig. 3.

I claim:

The ornamental design for a combined necklace and clip, substantially as shown.

SOL E. WEINREICH.
